UNITED STATES PATENT OFFICE.

BERNARD SCHAEFER, OF CINCINNATI, OHIO.

DESIGN FOR A COMBINED BOOK HOLDER AND LIGHTING FIXTURE.

Application filed March 5, 1926. Serial No. 16,803. Term of patent 7 years.

To all whom it may concern:

Be it known that I, BERNARD SCHAEFER, a citizen of the United States, residing at Cincinnati, county of Hamilton, and State of Ohio, have invented a new, original, and ornamental Design for a Combined Book Holder and Lighting Fixture, of which the following is a specification, reference being had to the accompanying drawing, forming a part thereof.

In said drawing, the figure is a perspective view of a combined book-holder and lighting fixture showing my new design.

I claim:

The ornamental design for a combined book-holder and lighting fixture as shown.

BERNARD SCHAEFER.
